UNITED STATES PATENT OFFICE.

RAYMOND A. MULL, OF BENTON HARBOR, MICHIGAN.

WRENCH.

Application filed June 16, 1924. Serial No. 720,204.

To all whom it may concern:

Be it known that I, RAYMOND A. MULL, a citizen of the United States, and resident of Benton Harbor, Berrien County, Michigan, have invented a certain new and useful Improvement in Wrenches, of which the following is a specification.

This invention relates to wrenches, and more particularly to those having a pivoted or self-adjusting engaging portion for one jaw of the wrench.

Generally stated, the object of the invention is to provide an improved and novel construction and arrangement whereby the connection between the movable or self-adjusting portion and the jaw upon which this portion is mounted, is of such character that there will be no danger of shearing or breakage of the pivotal or other connection between the jaw and said portion, when the wrench is used for the purpose for which it is intended.

It is also an object to provide certain details and features of construction tending to increase the general efficiency and the desirability of a wrench having a movable or self-adjusting face or engaging portion for one jaw thereof of this particular character.

To the foregoing and other useful ends the invention consists in matters hereinafter set forth and claimed and shown in the accompanying drawings in which—

Fig. 1 is a side elevation of a wrench embodying the principles of the invention, showing a portion of the handle broken away for convenience of illustration.

Fig. 2 is a similar view showing the head of the wrench in vertical section.

Fig. 3 is a horizontal section on line 3—3 in Fig. 2.

Fig. 4 is a perspective of one of the parts of the wrench.

As thus illustrated, the invention comprises a handle 1 which is rigid with the upper jaw 2, the lower jaw 3 having a portion 4 that slides up and down in the guideway 5 formed in the body portion 6 of the wrench. The portion 4 has teeth 7 to engage the screw 8 which is mounted upon an axis member 9 which is screwed into the body of the wrench, whereby rotation of the member 8 will cause up or down movement of the jaw 3 previously mentioned. The edges of the screw thread on the member 8 can be roughened to facilitate rotation thereof by the thumb and finger. The jaw 3 is provided

transversely with a groove 10 which is cylindrical and provided with a restricted opening 11 at its upper side. The self-adjusting engaging portion 12 is provided with a tongue 13 formed transversely thereof, on its under side, and this tongue 13 fits the groove 10 as shown. However, it will be seen that the neck portion 14 of this tongue is somewhat narrower than the opening 11 at the top of the groove, and hence the engaging portion 12 has some freedom of rocking movement about an axis extending transversely of the jaw 3, said axis being coincident with the axis of the cylindrical tongue 13 previously mentioned, and coincident with the axis of the cylindrical groove 10 previously mentioned. In other words, this forms a pivotal or oscillatory connection between the jaw 3 and the portion 12, the tongue being oscillatory in the groove in the manner shown and described. Of course, inasmuch as the opening 11 is narrower than the diameter of the tongue 13, it follows that the tongue must enter the groove endwise, and must be displaced endwise or axially therefrom, inasmuch as axial insertion and removal of the tongue 13 in the groove 10 is necessary with the construction shown and described. In order to lock the engaging portion 12 against lateral displacement, by axial movement of the tongue 13 in the groove 10, the said tongue is preferably provided on its under side with a notch 15, and a pin 16 is inserted through the jaw 3 into this notch, whereby the portion 13 is held against displacement, but at the same time has perfect freedom of rocking motion, the notch 15 being formed in a manner and of sufficient size for this purpose. To hold the portion 12 normally in the position shown, a coil spring 17 is seated in a socket 18 formed in the jaw 3, in position to bear upwardly against the under side of the inner end portion of the engaging portion 12, in the manner shown. The pin or other retainer 16 may be a loose pin, of course, disposed at one side of the spring 17, as shown, and in such event the pin is held against displacement by the body portion 6 of the wrench, as the end of the pin moves up and down against said body portion when the parts are properly assembled. With this construction, the portion 12 can rock about its axis or pivotal connection with the jaw 3, when the wrench is applied to any object which is to be turned, such as a pipe or a rod or other

object, and in this way the portion 12 will accommodate itself or adjust itself to the position most effective for turning the object to which the wrench is applied. The 5 tongue and groove 13 and 10 form a very strong pivotal connection between the portion 12 and the jaw 3, which will not be easily broken, for the pressure when the wrench is applied to an object is transmitted 10 through the portion 12 to the lower side of the tongue 13, and from this tongue to the jaw 3, and hence a pivotal connection is provided which cannot shear or break or be otherwise injured by the use of the wrench 15 in the usual and ordinary manner.

It will be seen that the top surface of the jaw 3 is level and horizontal, when the wrench is in the position shown in the drawings, and is parallel with the serrated or 20 toothed lower surface 19 of the upper jaw. It will also be seen that the rocking portion 12 has shoulders 20 and 21 formed at opposite sides of the tongue portion 13, these shoulders being disposed in planes extending 25 at an angle to each other. Furthermore, the jaw 3 has shoulders 22 and 23 at opposite sides of the groove 10 in the jaw 3, but these shoulders are in the same horizontal plane, whereby the rocking member 12 can rock to 30 either side, and either of these shoulders will engage one of the shoulders on the jaw to limit the motion. When the shoulder 21 engages the shoulder 23, it will be seen, the toothed or serrated surface 24 is substantially or in effect parallel with the lower 35 side 19 of the upper jaw; but when the member 12 is tilted outward, so that its shoulder 20 engages the shoulder 22, the surface 24 is then at an angle to the surface 19, as 40 shown. The spring 17, therefore, serves to hold the shoulder 20 normally against the shoulder 22, so that the rocking portion 12

is held normally in engagement with the outer end portion of the jaw 3, in the manner shown and described.

45

With the construction shown and described, it will be seen that the spring 17 can only be removed by first removing the jaw 3 from the wrench, and by then removing the pin 16, and by finally removing the 50 member 12 from this movable jaw. It is obvious that this can be done by first removing the screw 9, and then slipping the screw 8 out sidewise, so that the jaw 3 can then be displaced downwardly from the wrench. 55 When that has been done, and if the retainer 16 is a loose pin, it can then be dropped out by turning the jaw 3 over sidewise, and in this way there is no danger that the wrench will come apart when assembled, as 60 the pin 16 cannot possibly be removed while the parts are assembled, but at the same time the tilting member 12 can be easily removed when such is necessary or desirable.

65

What I claim as my invention is—

In a wrench, the combination of relatively movable jaws, a one-piece engaging member on one jaw, formed with a transverse integral portion which is oscillatory in the jaw, said member being removable 70 only by axial displacement thereof, a compression spring engaging the inner end portion of said member to keep its outer end normally pressed against the jaw, said integral portion having a notch, and a retainer 75 inserted in the jaw and extending into said notch, said jaw having said member being removable from said wrench, said retainer being a concealed loose pin inserted from the inner side of the removable jaw at one 80 side of said spring, so that the pin cannot be removed while the wrench is assembled.

RAYMOND A. MULL
